UNITED STATES PATENT OFFICE.

HERBERT E. HOLLOWAY, OF TRENTON, NEW JERSEY.

WATCHMAKER'S TWEEZERS.

1,081,830.

Specification of Letters Patent.

Patented Dec. 16, 1913.

Application filed May 17, 1913. Serial No. 768,253.

To all whom it may concern:

Be it known that I, HERBERT E. HOLLOWAY, a citizen of the United States, and a resident of Trenton, in the county of Mercer 5 and State of New Jersey, have invented a new and Improved Watchmaker's Tweezers, of which the following is a full, clear, and exact description.

My invention relates to watchmakers' 10 tweezers, and has reference more particularly to tweezers used for placing the overcoil hairspring in position in a watch.

When the hairspring of a watch is in position it should be perfectly flat. The ordinary flat hairspring is very easily adjusted 15 in position while in the watch. The overcoil spring is not so easily adjusted into position and invariably has to be removed from the watch to give it the necessary bend to 20 cause the main body of the spring to remain flat. Often this operation has to be repeated a number of times before the spring is in proper position. The reason the overcoil hairspring does not lie flat in a watch is be- 25 cause the overcoil is raised either too far or not far enough above the main body of the hairspring; and it is with difficulty that the spring can be bent correctly with the ordinary tweezers without first removing the 30 hairspring from the watch.

To overcome the necessity of taking out the overcoil hairspring when placing the same in position, I have invented a pair of tweezers which have their clamping ends bifurcated, one side of which is so curved that when the bifurcated ends of the tweezers engage the overcoil end of the hairspring in the watch, they cause the end of the spring to bend in the desired direction while the 40 main portion of the hairspring remains flat in the watch.

The invention consists of the construction and combination of parts to be more fully described hereinafter and fully set forth in 45 the claims.

Reference is to be had to the accompanying drawings forming a part of this specification, in which like characters indicate corresponding parts in all the views and in 50 which:

Figure 1 is a plan view of an embodiment of my invention; Fig. 2 is a side elevation of same; Fig. 3 is a side elevation of the tweezers closed; Fig. 4 is a section on line 55 4—4, Fig. 3, showing the bifurcated ex-

tremities of the tweezers engaging the overcoil end of the hairspring; and Fig. 5 is a side elevation of a pair of tweezers for bending the overcoil end of the spring in the opposite direction from the same side of the 60 watch.

Referring to the drawings, 6 and 7 represent the arms of the tweezers connected together at one end by means of rivets 8. The normal tendency of the arms 6 and 7 is to 65 spread the non-riveted ends apart about the rivets as a fulcrum. These non-riveted ends are each provided with central slots 9 and 10 respectively dividing the end of the arm 6 into two portions or sides 11 and 12 and the 70 end of the arm 7 into two portions or sides 13 and 14. The juxtaposed sides 11 and 13 of the arms 6 and 7 are bent or curved, as shown in Figs. 2 and 3, while the sides 12 and 14 of the bifurcated ends are flat and in 75 plane with the inner surface of the arms 6 and 7 respectively. The sides 11 and 13 of the bifurcated ends are so bent that one fits snuggly into the other; see Fig. 3.

In Fig. 5 the arms 6' and 7' have the sides 80 12' and 14' of the bifurcated ends curved, while the sides 11' and 13' are straight. This provision is to permit the bending of the overcoiled end of the hairspring in the direction opposite the one produced by the 85 ends of the tweezer arms 6 and 7, shown in Figs. 1 to 3 inclusive.

The application of the tweezers is shown in Fig. 4. While the sides 12 and 14 of the bifurcated ends of the arms 6 and 7 respectively maintain the portion of the hairspring 15 engaged therebetween flat, the ends 11 and 13 of the bifurcated ends of the arms 6 and 7 respectively causing the end of the spring engaged between them to be 95 twisted, so as to cause the stud attached to the extremity of the overcoiled end to descend to or rise from the main body of the spring, according to the type of tweezers used, that is, those shown in Figs. 1 to 3 inclusive or that shown in Fig. 5.

Having thus described my invention, what I claim as new and desire to secure by Letters Patent is:

1. Watchmakers' tweezers having their 105 clamping ends bifurcated, each of said ends having one branch of the bifurcation flat and the other curved, substantially as and for the purpose set forth.

2. Watchmakers' tweezers having their 110

clamping ends bifurcated, each of said ends having one branch of the bifurcation flat and the other branch curved, the curved branches of the two ends coacting with each 5 other, substantially as and for the purpose set forth.

3. Watchmakers' tweezers having their clamping ends bifurcated, said bifurcations of each end having one of the facing 10 branches of the same curved so as to fit

snugly one into the other, substantially as and for the purpose set forth.

In testimony whereof I have signed my name to this specification in the presence of two subscribing witnesses.

HERBERT E. HOLLOWAY.
